AUTOMATICALLY-INFLATABLE LIFE
PRESERVERTed J. Kubit, 19332 Montrose Ave., Detroit 35, Mich.,
and William S. Stanton, 3643 Wakefield Ave., Berkley,
Mich.Filed June 19, 1961, Ser. No. 117,950
2 Claims. (Cl. 9—317)

This invention relates to life preservers and, in particular, to automatically-inflatable life preservers.

One object of this invention is to provide an automatically-inflatable life preserver wherein a compressed gas cartridge or flask is automatically punctured to cause this gas to flow into the inflatable life preserver in response to the dissolving of a pellet of water-soluble material brought about by the presence of the wearer of the life preserver in water.

Another object is to provide an automatically-inflatable life preserver of the foregoing character wherein the automatic inflating device is capable of being carried, together with the rolled-up or folded life preserver, in a compact package upon the wearer, such as in the wearer's pocket, or in a shoulder holster or other convenient carrier.

Another object is to provide an automatically-inflatable life preserver of the foregoing character wherein the mechanism for puncturing the compressed gas cartridge or flask is adapted to be inactivated during periods of storage or transportation, but is adapted to be quickly and easily activated so as to be instantly ready for use in the event of the wearer falling or otherwise finding himself in the water.

Another object is to provide an automatically-inflatable life preserver of the foregoing character wherein a spring-actuated puncturing device is held in a cocked position but prevented from puncturing the gas flask or cartridge by a pellet or tablet of water-soluble material, such as a sugar cube, which upon dissolving in the water releases the spring-pressed mechanism to puncture the flask and thus inflate the life preserver.

Another object is to provide an automatically-inflatable life preserver, of the foregoing character, wherein a manually-operable puncturing device is provided for manual operation by the user in a manner auxiliary to the automatic puncturing mechanism, if for any reason the automatic mechanism should fail to function or should inadvertently have been left in its inactivated condition.

Other objects and advantages of the invention will become apparent during the course of the following description of the accompanying drawings, wherein:

FIGURE 1 is a top plan view, partly in horizontal section, of an automatically-inflatable life preserver, according to one form of the invention, with the cover plate removed and the major portion of the life preserver itself omitted to conserve space and with the mechanism in its uncocked or inactivated condition;

FIGURE 2 is a vertical longitudinal section taken along the line 2—2 in FIGURE 1; with the cover plate in position;

FIGURE 3 is a vertical cross-section taken along the line 3—3 in FIGURE 1, also with the cover plate in position;

FIGURE 4 is a fragmentary horizontal section taken along the line 4—4 in FIGURE 3, with the manual puncturing cam lever omitted to disclose the parts beneath it;

FIGURE 5 is a top plan view similar to FIGURE 1, but with the puncturing mechanism in its cocked or activated position;

FIGURE 6 is a top plan view similar to FIGURES 1 and 5, but with the soluble pellet or tablet dissolved by immersion in water and the puncturing mechanism in its

2

"fired" or actuated position after puncturing the gas flask; FIGURE 7 is a fragmentary top plan view similar to FIGURE 5 but with the manual flask-puncturing mechanism shown in its operated position after puncturing the gas flask;

FIGURE 8 is a front elevation of the upper part of the body of a wearer of the life preserver, showing the latter carried in a shoulder mounting;

FIGURE 9 is a view similar to FIGURE 8 but showing the life preserver carried in the user's breast pocket;

FIGURE 10 is a view similar to FIGURE 8 but showing the wearer in the water and the life preserver automatically inflated as the result of such immersion; and

FIGURE 11 is a perspective view of the automatically-inflatable life preserver shown in FIGURES 1 to 10 inclusive.

Referring to the drawings in detail, FIGURES 1 and 11 show an automatically-inflatable life preserver, generally designated 20, according to one form of the invention as consisting generally of an inflatable life preserver 22 of any suitable form, the form shown being a life belt made of rubber or the like. The life belt is adapted to be filled by means of a compressed gas, such as carbon dioxide, from an automatic inflating device, generally designated 24, by way of an inflating tube 26 leading to a connection 28 with the interior of the inflatable life belt 22.

The automatic inflating device 24 to which the inflating tube 26 is connected is mounted in a box-shaped casing 30 of aluminum, plastic or other light water-resistant and durable material. The casing 30 along one side is provided with a pocket or recess 32 in which is mounted a conventional compressed gas flask or cartridge 34, such as a carbon dioxide cartridge of the type commonly used in beverage carbonating siphon bottles. The cartridge 34 has a neck 36 which terminates in a rupturable end closure 38 (FIGURE 1), the neck 36 extending loosely through an enlarged hole 40 in the wall 42 of the pocket 32 in such a manner that the flask or cartridge 34 can move longitudinally toward a hollow puncturing needle 44. The puncturing needle 44 projects inwardly toward the flask end closure 38 from a threaded plug 46 which in turn is threaded into an internally-threaded bore 48 in the casing 30, closing the inner end of the threaded bore 48. The outer end of the threaded bore 48 is closed by a threaded plug 50 spaced axially away from the plug 46 to provide a chamber 52 with which the passageway 54 of the hollow puncturing needle 44 communicates. The casing wall portion 56 containing the threaded bore 48 is threaded transversely as at 58 to receive the threaded coupling 60 at the inner end of the inflating tube 26. The casing wall portion 56 is also threaded transversely to receive a locking set screw 62 for locking the puncturing needle plug 46 within the inner end of the bore 48.

The casing 30 also contains a spring pocket 64 in which a tension spring 66 is mounted. One end 68 of the tension spring 66 (FIGURE 1) is hooked into an internally-threaded flanged collar or nut 70, the threaded bore 72 of which is threadedly engaged by a screwshaft 74. The screwshaft 74 passes loosely through the casing end wall portion 78 which is suitably drilled for that purpose, and terminates in a head 80 which is transversely drilled to receive a winding handle or crank 82. The latter is pivotally mounted in the head 80 so as to be capable of being swung from the inoperative position of FIGURES 1, 5 and 6 to the operative position of FIGURE 11. In order to avoid straining the spring 66, it is normally adapted to be maintained in the relaxed condition shown in FIGURES 1 and 11 and is stretched into a tensioned condition by rotating the screwshaft 74 by means of the crank 82 swung into the operating position of FIGURE 11 so as

to cause the internally-threaded collar 70 to move outward from the position shown in FIGURES 1 and 11 to the position shown in FIGURES 5 and 6, whereupon the crank or handle 82 may be swung back into the inoperative position within the casing 30 as shown in FIGURES 1, 5 and 6.

The opposite end 34 of the spring 66 is also bent and hooked into a hole 86 in the outer end of a lower cam lever 88, the inner end of which carries a lower cam 90 and is drilled eccentrically thereto for pivotal mounting 10 upon a pivot screw 92 threaded into a threaded bore 94 in the bottom wall 96 of the casing 30 (FIGURE 3). The lower cam lever 88 is provided with an arm 98 carrying a downwardly-extending lug 100 forming a sear, by analogy to firearms, engaged by an upstanding lug 102 15 which in turn is struck up from a trigger lever 104. Near the lug 102, the trigger lever 104 is drilled to receive a pivot screw 106 (FIGURE 3) upon which it is pivotally mounted to swing between the positions shown in FIGURES 5 and 6. The trigger lever 104 near its outer end 20 is provided with outer and inner stepped edges 108 and 110 respectively cooperating with an abutment wall 112 (FIGURE 1) to hold either small sugar cube 114 (shown in dotted lines in FIGURE 1) or a large sugar cube 116 (shown in solid lines therein). The sugar cube 114 or 25 116 is held against the abutment wall 112 by the tension of the spring 66 acting through the lower cam lever 88 against the trigger lever 104 through the coacting lugs 100 and 102.

Also drilled eccentrically to be pivotally mounted on the pivot screw 92 is an upper or manual cam lever 118 also having a cam 120 thereon similar to the cam 90 previously described and having its outer end provided with a hole 122 for receiving one end of a knotted pull cord or cable 124 which passes through a hole 125 in the abutment wall 112, the opposite end also being knotted and carrying a handle knob 126. The cams 90 and 120 in their cocked positions are adapted to engage the rounded rearward end 128 of the compressed gas flask 34 so as to move the latter longitudinally within its socket 32 when either of 30 the cam levers 88 or 118 is swung around the pivot screw 92 to rotate the cam 90 or the cam 120, as explained 35 below in connection with the operation of the invention. The casing 30 is closed by a transparent cover plate 130 secured thereto by screws 132 in holes 134 (FIGURES 3 and 11).

In the operation of the invention, let it be assumed that before going near the water the user of the automatically-inflatable life preserver 20 of this invention has prepared it for instant use. To do so, he first inserts a compressed gas cartridge or flask 34 of carbon dioxide or other suitable gas in the pocket 32 after inserting the neck portion 36 thereof in the hole 40 through the partition wall 42 (FIGURE 1), then dropping the rearward end 128 into the pocket 32 in line with the lower and upper cams 90 and 120. He then inserts a water-soluble pellet or tablet 114 or 116 in the pocket 64 against the abutment 50 112, either a small sugar cube 114 or a large sugar cube 116 being found suitable for this purpose. The cube 114 or 116 is inserted while the trigger lever 104 is swung to the right into the position shown in FIGURES 1, 5 and 11. The user now swings the crank 82 into its operative position shown in FIGURE 11 and rotates the screwshaft 74 so as to move the internally-threaded flanged collar or nut 70 from its spring-relaxing position of FIGURE 1 to its spring-tensioning position of FIGURE 5. The crank 82 is then swung back into its inoperative position (FIGURE 1).

At this time, the lower cam lever is held in its cocked position by the trigger lever 104 and water soluble tablet or pellet 114 or 116. The parts are now in the relative positions shown in FIGURE 5, with the mechanism fully cocked and ready for instant operation. The user then either fastens the life preserver 20 in his breast pocket with the life belt 22 rolled up, as shown in FIGURE 9, such 70 75

as by a clip 136 (FIGURE 9), or suspends it from his shoulder by a shoulder strap 138 (FIGURE 8) with the life belt 22 strapped around his chest beneath his armpits.

Let it be assumed that the user falls or is forced to jump into the water either by accident or intention, such as by the occurrence of a fire or other disaster aboard his boat. The water rushes in through the hole 125 and through the crack between the cover 130 and the casing 30, as well as through the hole for the screwshaft 74, and acts upon the soluble material of the tablet 114 or 116, dissolving it. When the tablet 114 or 116, for example a sugar cube (FIGURE 5) has disintegrated under the action of the water, the spring 66 pulls the lower cam lever 88 in a counterclockwise direction around the pivot screw 92, pushing aside the trigger lever 104 by its sliding engagement therewith through the lugs 100 and 102. This action causes the lower cam 90 to rotate, pushing against the inner end 128 of the compressed gas cartridge 34, urging the closure 38 against the hollow puncturing needle 44 and causing the latter to penetrate the former. The parts are now in the relative positions shown in FIGURE 6. The compressed gas within the cartridge or flask 34 rushes out through the passageway 54 in the hollow needle 44 by way of the chamber 52 and the inflating tube 26 into the inflatable life belt 22, inflating the latter. The thus inflated life belt, supporting the user, is shown in FIGURE 10, where the life belt 22 has been strapped around the chest of the user. The life belt 22 in FIGURE 9 by such inflation would unroll, leaving it to the user to strap it around his body.

If for any reason the automatic puncturing mechanism fails to work in the above manner, such as, for example, if the user had inadvertently neglected to rotate the screwshaft 74 to tension the spring 66 and cock the mechanism, the user merely grasps the knob 126 and gives a jerk to the cord 124. This action swings the upper cam lever 118 in a counterclockwise direction from the position shown in FIGURE 1 to that shown in FIGURE 7, rotating the upper cam 122 in such a manner as to push the closure 38 of the compressed gas flask 34 against the hollow puncturing needle 44, puncturing the closure 38 and causing the gas to flow out and inflate the life belt 22 in the manner previously described.

After use, to prepare the device 20 for re-use, the operator removes the screws 132 and the cover plate 130, takes out the empty punctured gas cartridge 34, and swings the upper and lower cam levers 118 and 88 and the trigger lever 104 clockwise into the positions shown in FIGURE 1. He then inserts a new compressed gas cartridge 34 in the pocket 32 with its neck portion 36 projecting loosely through the hole 40, and places another sugar cube or other soluble tablet or pellet 114 or 116 in position holding the trigger lever 104 and lower cam lever 88 in their cocked positions. If the device is to be stored, the user swings the crank 82 into its operative position and rotates the screwshaft 74 reversely so as to return the nut 70 from its spring-tensioning position of FIGURES 5 and 6 to its relaxed position of FIGURE 1, returning the crank 82 to its position within the casing 30 when this action has been completed.

What we claim is:

1. An automatically-inflatable life preserver, comprising
a buoyant inflatable gas receptacle having a gas inflation inlet,
a supporting structure,
a stationary hollow puncturing element fixedly mounted on said structure in communication with said inlet,
said structure having a compressed gas cartridge holder disposed adjacent said puncturing element,
a pivot element mounted on said structure;
a gas cartridge moving member including a lever pivotally mounted on said pivot element adjacent said gas cartridge holder and having a rotary cam thereon dis-

posed eccentric to said pivot element and engageable with one end of the gas cartridge, a spring connected to said gas cartridge moving lever and operative to swing said gas cartridge moving lever to rotate said cam and consequently push the gas cartridge into puncturing engagement with said puncturing element, and means responsive to the presence of a water soluble body for restraining said cartridge-moving lever from cartridge-moving motion and responsive to the dissolution of the water soluble body for releasing said cartridge-moving lever for cartridge-moving motion, said restraining means including a locking lever pivotally mounted on said structure and having a trigger portion engageable with the water soluble body and a locking portion movable out of locking engagement with said cartridge-moving member in response to the swinging of said trigger portion consequent to the dissolving of the water-soluble body.

2. An automatically-inflatable life preserver, comprising

a buoyant inflatable gas receptacle having a gas inflation inlet,

a supporting structure,

a stationary hollow puncturing element fixedly mounted on said structure in communication with said inlet, said structure having a compressed gas cartridge holder disposed adjacent said puncturing element,

a pivot element mounted on said structure,

a gas cartridge moving member including a lever pivotally mounted on said pivot element adjacent said gas cartridge holder and having a rotary cam thereon dis-

20

25

30

posed eccentric to said pivot element and engageable with one end of the gas cartridge, a spring connected to said gas cartridge moving lever and operative to swing said gas cartridge moving lever to rotate said cam and consequently push the gas cartridge into puncturing engagement with said puncturing element, means responsive to the presence of a water soluble body for restraining said cartridge-moving lever from cartridge-moving motion and responsive to the dissolution of the water soluble body for releasing said cartridge-moving lever for cartridge-moving motion, said supporting structure having a bearing portion disposed coaxial with said spring, and adjusting means including a screw-threaded spring abutment connected to one end of said spring and a rotary screw shaft journaled in said bearing portion and disposed in threaded engagement with said spring abutment for selectively rendering said spring cocked and relaxed.
